RECESSED LIGHTING FIXTURE

Henry Rosenfeld, South Euclid, Ohio, assignor to American Lantern and Manufacturing Company, Cleveland, Ohio, a corporation of Ohio

Application April 1, 1958, Serial No. 725,690

2 Claims. (Cl. 240—78)

This invention relates generally to recessed lighting fixtures.

Lighting fixtures have heretofore been employed, comprising a recess box disposed in a recess in a ceiling, and a junction box adjacent the recess box and through which access to the junction box may be had through an opening in the wall of the recess box.

In most cases, however, access to the junction box has been difficult, due to the necessity of removing panels which cover the opening in the wall of the recess box, or because the openings and panels are rather small and inaccessible, or for other reasons.

The present invention has as its primary object the provision of a recessed lighting fixture of the character described in which access to the junction box may be had through a relatively large and easily accessible opening in the wall of the recess box, thereby greatly facilitating such access.

Another object of the invention is to provide a fixture of the character described, in which a reflector, which is a part of the fixture, is utilized, in a novel manner, to conceal the junction box and the access opening thereto.

A further object of the invention is to provide a fixture of the character described, in which novel means are incorporated for permitting quick and easy removal of the reflector.

A still further object of the invention is to provide a fixture of the character described, which consists of a minimum number of easily fabricated and readily assembled parts of light weight construction.

Other objects and advantages of my invention will be apparent during the course of the following description.

In the accompanying drawings forming a part of this specification, and in which like numerals are employed to designate like parts throughout the same,

Fig. 1 is a top plan view of a recess lighting fixture, embodying the invention, with a portion thereof broken away to better illustrate certain parts;

Fig. 2 is a bottom plan view of the fixture;

Fig. 3 is a side elevational view of the fixture, as viewed from the right side of Fig. 1, but with the reflectors removed;

Fig. 4 is a cross-sectional view, taken on the line 4—4 of Fig. 1;

Fig. 5 is a cross-sectional view, taken on the line 5—5 of Fig. 1, but with the reflectors removed;

Fig. 6 is a fragmentary view, on an enlarged scale, of a portion of Fig. 4, and

Fig. 7 is a fragmentary cross-sectional view, taken on the line 7—7 of Fig. 6.

Referring more particularly to the drawings, the fixture will be seen to comprise a box having a rectangular front panel 1 and a similar rear panel 2. The front panel 1 is provided with side flanges 3 and 4 and a top flange 5, and the rear panel 2 is likewise provided with side flanges 6 and 7 and a top flange 8. The side flanges 3 and 6 are coplanar as are the side flanges 4 and 7. The top flanges 5 and 8 are also coplanar.

2

In order to form a rigid box-like structure, a side panel 9 is used to interconnect the flanges 3 and 6, as by means of rivets 10, and a similar side panel 11 is used to interconnect the flanges 4 and 7, as by means of rivets 12.

As shown in Fig. 3, the side panels 9 and 11 are approximately half the height of the panels 1 and 2, leaving spaces 13 above the panels 9 and 11, the function of which will be presently described.

Secured to the top flanges 5 and 8, as by means of rivets 14, is a narrow bar 15, which extends from the front to the rear of the box. Threadedly secured to the center of this bar 15, and depending therefrom, is a screw 16 having a head 17.

Secured to the bar 15, as by the head 17 of the screw 16 (see Fig. 6), is a reflector, of generally frusto-pyramidal form comprising a top 18 and sloping sides 19, 20, 21 and 22, these sides extending to the bottom of the box and having flanges 23 which underlie the lower edges of the panels 1, 2, 9 and 11, as best shown in Figs. 2 and 4.

Also secured to the bar 15, as by the head 17 of the screw 16, is a dome-shaped reflector 24, having a portion of its periphery cut away to provide a recess 25, through which the neck of a light bulb (not shown) extends.

The fixture also includes a light bulb socket 26, which is supported by a bracket 27, which is secured to the panel 2, as by rivets 28. The socket 26, as will be seen in Figs. 1, 2 and 4, projects into the space within the reflector 18—22 through an opening 29 provided in the side 21 of the reflector.

The fixture further includes a junction box 30, which as shown in Figs. 1 and 2, is supported in laterally spaced relation to the recess box. This support is economically provided by providing the bottom 31 of the junction box with an extension 32, which in turn, is provided with a downturned flange 33, which is secured to the inner face of the upper portion of the panel 11, as by screws 34. The extension 32 extends through the space 13 above the panel 9.

The junction box 30 is provided with a removable cover 35, secured to the box 30, as by screws 36, so that access to the interior of the junction box may be had through the space 13, after the removal of the cover 35.

The wires from the junction box 32 to the socket 26 are carried through a metal conduit 37, which is supported by the junction box and terminates as at 38, within a hollow shield 39. The shield 39 is interposed between the panel 9 and the socket 26, and is provided with a plate-like extension 40 (see Figs. 1, 4 and 5) which is clamped between the base of the socket 26 and the bracket 27, thereby providing a means of supporting the shield 39 without extra screws.

In order to permit access to the junction box 30, for inspection or repair purposes, without requiring removal of the fixture from the recess in the ceiling, means have been provided for permitting easy removal of the reflectors 18 and 24 from the recess box. Such means is best illustrated in Figs. 2, 4, 6 and 7. For this purpose, the reflector 18 is provided with an opening 41 of a diameter larger than the diameter of the head 17 of the screw 16, and from which a slot 42 extends radially, the slot 42 being of a width substantially the same as the diameter of the stem of the screw 16. Similarly, the reflector 24 is provided with an opening 43 of approximately the same diameter as that of the opening 41, and from which a slot 44 extends radially, the slot 44 being of a width substantially the same as the width of the slot 42.

When access to the junction box is desired, the light bulb (not shown) is first removed from the socket 26, after which the head 17 of the screw 16 is turned to release it from clamping engagement with the reflector 24. The reflectors 24 and 18 are then moved in a downward direction, as viewed in Figs. 4, 6 and 7, sufficient

ly to bring the openings 43 and 41 opposite the head 17 of the screw, after which the reflectors may be removed from the recess box. A slight tilting of the reflector 18 may be necessary while removing the reflector from the recess box. Following such removal, the hand may be extended through the opening 13 above the panel 9, to remove the cover 35, and gain access to the interior of the junction box.

Due to the skeletonized construction of the recess box, the box has strength, and, at the same time, the opening 13 is so large in area as to permit easy access to the junction box. This opening is further enlarged by the fact that the bar 15 is narrow, leaving considerable space at the sides of the bar.

It will also be noted that the panels 9 and 11 have secured to the inner walls thereof brackets 45, having slots 46 therein. These brackets are utilized for the attachment of a cover (not shown) to the recess box. The sides 20 and 22 of the reflector 18 are cut away, as at 47, to permit the attachment means for the cover to be entered in the slots in the bracket.

It is thus seen that I have provided a recessed lighting fixture which admirably fulfills all of the stated objects of the invention, and which is of economical construction.

It is to be understood that the form of my invention, herewith shown and described, is to be taken as a preferred example of the same, and that various changes may be made in the shape, size and arrangement of parts of my invention, without departing from the spirit of the invention or the scope of the subjoined claims.

I claim:

1. A lighting fixture of the wall-recessed type, comprising a box-like structure having front and rear panels,

and side panels extending vertically upward from a horizontal plane defined by the lower edges of the front and rear panels and of substantially less height than the front and rear panels, whereby to provide large openings above the side panels, a junction box supported by one of said side panels, in substantially spaced relation to said panel, a reflector mounted in said structure, and having sloping side walls which normally block access to said openings, said reflector being removable from said structure, whereby access to said junction box may be had through one of said openings, and means for supporting said reflector, said means comprising a bar interconnecting said front and rear panels, a screw secured to said bar and having an enlarged head, and an opening in said reflector having an enlarged portion larger than said head and a slot extending radially from said enlarged portion, said slot being of a width substantially the same as the diameter of the stem of said screw.

2. A fixture, as defined in claim 1, including a dome-like reflector supported by the head of said screw, said last-named reflector having an opening with an enlarged portion larger than said head and a slot extending radially from said enlarged portion and of a width substantially the same as the diameter of the stem of said screw.
